UNITED STATES PATENT OFFICE.

QUINCY G. SHELDON, OF ELBURN, ILLINOIS.

DEVICE FOR PLACING METAL REINFORCING.

1,183,128.

Specification of Letters Patent.

Patented May 16, 1916.

Application filed February 12, 1915. Serial No. 7,750.

To all whom it may concern:

Be it known that I, QUINCY G. SHELDON, a citizen of the United States, residing at Elburn, in the county of Kane and State of Illinois, have invented certain new and useful Improvements in Devices for Placing Metal Reinforcing, of which the following is a specification.

My invention has relation to a device for placing and holding metal reinforcing in mold bodies, such as are used for forming concrete fence posts or similar articles, so as to insure the proper location of the reinforcement to the finished product.

My device is particularly adapted for use in connection with the horizontal, open-face type of molds in which a plurality of mold bodies are nested in a framework with their open sides up.

It is well known that in making concrete fence posts or the like, reinforcement, usually in the form of a plurality of steel rods or bars, is embedded in the concrete while the post is being formed to give the same its necessary tensile strength. It is also desirable and the practice, when concrete of what is known as the "wet mix" is used, to shake or vibrate the mold bodies in various ways while the post is being formed for the purpose of compacting the concrete and to work out air and water pockets which may form therein.

The principal objects of my invention comprehend the production of a device of the above character, by means of which the reinforcing rods can be placed in all of the mold bodies in a framework at one time, preparatory to filling the same with the concrete mixture; which will serve to rigidly hold the reinforcement in proper position while the molds are being filled as well as vibrated; which has means for simultaneously releasing all of the reinforcing rods, after which the device is removed, leaving nothing in the finished product except the reinforcement; and which will be extremely easy to operate and inexpensive to manufacture.

Other objects and their resultant advantages will become apparent as the nature of my invention is better understood from the following description and accompanying drawings, in which latter:

Figure 1 is a bottom plan view with parts broken away and showing the reinforcing rods in dotted lines. Fig. 2 is an end elevation of Fig. 1. Fig. 3 is a detail view show-

ing the clamps closed in full lines and open in dotted lines. Fig. 4 is a perspective view of the crank arm of one of the clamps. Fig. 5 is an enlarged sectional view taken on the line 5—5 of Fig. 6. Fig. 6 is a top plan view showing my device in position for use upon the mold. Fig. 7 is a side elevation looking in the direction indicated by the arrow in Fig. 2.

For the purpose of illustrating the application of my device, I show in the drawings a standard type of open-face post mold, such as is now on the market and which comprises, broadly speaking, a plurality of mold bodies 1, nested in a framework consisting of head blocks 2, connected together by means of side bars 3, the mold bodies being arranged with their large and small ends alternating and with their open sides up.

Structurally, my invention consists of a pair of end pieces or supports 5 which are adapted to rest upon the mold bodies 1 transversely thereof when the device is in use as shown in Figs. 5 and 6. These end supports 5 are spaced and held the desired distance apart by means of connecting rods 6 securely fastened at each end to the supports 5 by nuts 7. With this arrangement it will be seen that by simply removing the nuts 7 from the ends of the rods 6, the device can be easily knocked down for convenience in packing and shipping.

Carried by each of the supports 5 is a series of clamps each comprising a stationary arm 8 and a crank arm 9, which latter is free to rotate in the supports 5 to effect the opening and closing of the clamps, as will be hereinafter described.

The stationary arms 8 are held rigid with respect to the supports 5 in any desired manner, as for instance, by having their upper ends offset as at 10 and inserted into a suitable aperture formed in the supports 5. The crank arms 9, loosely mounted in the end supports 5, extend above the upper edge thereof, where they are provided with cranks 11, the vertical arms 12 of which are all loosely connected to a single pitman bar 13. The clamp arms 8 and 9 are preferably formed of steel rods and have their free ends projecting beyond the lower edge of the end supports 5 and adapted, when the device is in use, to extend down into the mold bodies 1 the desired distance, as shown in Fig. 5. That portion of the crank arms 9 extending below the supports 5 are flattened and have

their edges, which lie adjacent the stationary arms 8 when the clamps are closed, provided with notches 14 for receiving the reinforcing rods 15.

5 The means I preferably employ for operating the clamps comprise a longitudinally extending lever 16 pivoted as at 17 to one end of each of the pitmans 13, and a link 18 pivotally connected to the lever 16 at a point 10 suitably removed from the pivot 17, as indicated at 19. The other end of the link 18 is, in turn, pivoted at 20 to the end supports 5. When the clamps are closed, as shown in full lines in Fig. 3, the lever 16 15 will lie substantially parallel with the connecting rod 6 and for the purpose of locking the same in this position, its free end is formed with an upstanding hook 21 adapted to fit over the rod 6, and thus prevent the 20 lever 16 being accidentally shifted to open the clamps.

In setting the clamps in the end supports 5 they are so spaced apart that the distance between the notches 14 in the crank arms 9 25 and the side of the adjacent stationary arms 8 will be just a trifle less than the thickness or diameter of the re-inforcing rods to be used, whereby when the same are placed into the notches and the crank arms 9 are 30 closed, the rods will impinge against the stationary arms 8 and thus be firmly held in place.

In use, the device is suspended in a vertical position with the clamps extending 35 outward and with the notches 14 of the crank arms 9 presented in an upward direction, the operating levers 16 being at the top of the device. This may be done by placing one of the connecting rods 6 over 40 pegs driven into a wall or other suitable structure. The hooks 21 are then disengaged from the connecting rod 6, thus permitting the free ends of the lever 16 to be forced downwardly. The link 18 will then act as a 45 fulcrum for the lever 16 and the same will swing on its pivot 19, its pivoted end 17 causing the pitman bar 13 to travel in an upward direction. This movement of the pitman will turn all of the cranks 11 pivoted 50 thereto and cause the crank arms 9 to rotate in the end supports 5, their edges in which the notches 14 are formed moving 55 away from their adjacent stationary arms 8. The reinforcing rods 15, which have been previously cut to the desired length, are then 60 assembled in the clamps by inserting the same sidewise between the arms 8 and 9 of said clamps so that they will rest in the notches 14. The rods resting in the notches 65 14 of the first crank arm 9 in one of the end supports 5, will also rest in the corresponding notches of the first crank arm on the other end support and so on until all of the notches are occupied. When the clamps are 70 fully opened, the flattened ends of the crank

arms 9 will extend at right angles with respect to the end supports 5, as shown in Fig. 3. However, for the purpose of assembling the reinforcing rods 15, the clamps are opened only about half way, or just enough 75 to permit the rods to pass between the arms 8 and 9, so that one side of the notches 14 will be sufficiently above a horizontal plane to retain the reinforcing rods therein until the clamps are closed. The free ends of the 80 levers 16 are then raised, thus forcing the pitmans 13 downward and causing the crank arms 9 to rotate in the end supports 5 until the notches 14 come into alinement with the stationary arms 8, thereby firmly gripping 85 the reinforcing rods in the clamps at each end of the device, as shown in Fig. 1. The device is then placed upon the molds, as shown in Figs. 5 and 6, the end supports 5 resting upon the mold bodies 1, and the clamps 90 carrying the reinforcing rods extending down into the same. As in the present instance, where the mold bodies are tapered, with their large and small ends alternating, and it is desired to have four reinforcing 95 rods 15 embedded in each post, the clamps are correspondingly arranged and spaced in the end supports so that two pairs of clamps will extend down into each of the mold bodies, one pair to fit the large end of the 100 mold body and the other pair to fit its small end. The molds are now filled with the concrete mixture and after the same has been made compact or dense, either by vibrating the molds or otherwise, the clamps are 105 opened to their full extent in the manner above described. This will leave the reinforcement entirely free of the clamps and the device may now be lifted off the molds and is ready for use again. In this way, 110 nothing but the reinforcement will be left in the finished post and any holes caused by the removal of the clamps, which may remain open, can be readily closed with a trowel. It will therefore be seen that by 115 properly spacing the respective pairs of clamps, as well as the notches 14 in the crank arms 9, the exact location of the reinforcement in the post to secure the maximum benefit therefrom can be accurately accomplished. 120

While I have shown and described my device in its present embodiment, it will easily be seen that by simply altering the general arrangement of the parts, such as the clamp arms 8 and 9 and the notches 14, the device can be made to work equally as well with different kinds of reinforcement or with 125 various types and shapes of molds. Also the particular construction of the several parts of my device could be changed in a number of ways without departing from the spirit of my invention and I therefore do not wish to be limited to the exact structure shown. 130

What I claim as new and desire to secure by Letters Patent is:—

1. A molding device for placing metal reinforcements comprising a mold, a frame adapted to be supported by said mold, consisting of end supports, a plurality of clamps depending from the end supports, for holding the reinforcing, each of said clamps comprising a stationary arm and a 10 crank arm and means for turning said crank arms to open and close the clamps.

2. A molding device for placing metal reinforcements comprising a mold, a frame adapted to be supported by said mold, consisting of end supports, a plurality of clamps depending from the end supports, for holding the reinforcing, each of said clamps comprising a stationary arm and a crank arm, cranks formed on the upper ends of 20 said crank arms, a pitman bar connecting said cranks and means for reciprocating said pitman bar, thereby turning said crank arms to open and close said clamps.

3. A molding device for placing metal reinforcements comprising a mold, a frame adapted to be supported by said mold, consisting of end supports, a plurality of clamps depending from each of said end supports and arranged in longitudinal alinement with respect thereto, each of said clamps comprising a stationary arm rigidly held in the end support and a crank arm rotatably mounted therein, the depending ends of said clamp arms being flattened and 35 having one edge provided with notches for receiving the reinforcing, cranks formed on the upper ends of said crank arms, a pitman bar connecting said cranks, and means for reciprocating said pitman bar, whereby

movement thereof in one direction will cause 40 the crank arms to rotate and their notched edges to move into alinement with the adjacent stationary arms, thereby clamping the reinforcing therebetween, while movement of said pitman in the other direction 45 will rotate the crank arms to cause their notched edges to move away from said stationary arms, and thereby release said reinforcing.

4. A molding device for placing metal reinforcements comprising a mold, a frame adapted to be supported by said mold, consisting of end supports, a plurality of clamps depending from the end supports, for holding the reinforcing, each of said 55 clamps comprising a stationary arm and a crank arm, cranks formed on the upper ends of said crank arms, a pitman bar connecting said cranks, a lever pivoted at one end to said pitman bar, a fulcrum link having one 60 end pivoted to said lever and its other end to the end support, whereby the swinging of said lever will reciprocate the pitman bar, thus turning said crank arms to open and 65 close the clamps.

5. A molding device for placing metal reinforcements comprising a mold, a frame adapted to be supported by said mold, a plurality of co-acting clamps carried by said frame for holding the reinforcements 70 and adapted to extend down into the mold when the frame is in position thereon, and means carried by said frame to operate said clamps simultaneously.
